HEADBOARD FOR A BED

Bert J. Klein and Andre Bus, Altavista, and John B. Thorn, Lynchburg, Va.

Filed Apr. 19, 1965, Ser. No. 84,848

Term of patent 14 years

(Cl. D5—4)

Fig. 1.

Fig. 2.

The back of the headboard is plain and unornamented.
We claim:

The ornamental design for a headboard for a bed, as shown and described.
